Seward Davis

UNITED STATES PATENT OFFICE.

JOHN STEWART THOMSON, OF LITTLE FALLS TOWNSHIP, PASSAIC COUNTY, NEW JERSEY, ASSIGNEE TO THE JARDINE MANUFACTURING CORPORATION, OF NEW YORK, N. Y., A CORPORATION OF NEW YORK.

FIRE-EXTINGUISHING DEVICE.

1,233,290

Specification of Letters Patent. Patented July 10, 1917.

Application filed October 29, 1915. Serial No. 58,521.

To all whom it may concern:

Be it known that I, JOHN STEWART THOMSON, a citizen of the United States, residing in the township of Little Falls, county of Passaic, and State of New Jersey, have invented certain new and useful Improvements in Fire-Extinguishing Devices, of which the following is a specification.

This invention relates to a fire extinguishing device, and more specifically to one employing an extinguishing fluid adapted to be forcibly ejected from a container at a point exterior thereto through a nozzle normally positioned therein, and to means for instantaneously placing the contained extinguishing fluid under pressure, and means for releasing said pressure either manually or automatically upon a predetermined rise in temperature.

One of the objects of my invention is to provide a portable fire extinguisher of simplified construction adapted to be positively operated to expel its contained fire extinguishing fluid, and capable of permitting the extinguishing fluid to be ejected in a spray upon a fire through a nozzle adapted to be projected from said container but normally to be positioned therein, and capable of directing said spray and of delivering it at constant pressure and more directly to the fire than other forms of apparatus. Another object of this invention is to provide a thermally controlled extinguisher of the kind described which shall automatically bring the sprinkling means into operation and deliver the extinguishing fluid under an instantaneously generated pressure. A further object is to provide an extinguisher of the class described which shall be simple and efficient in operation and which may be manufactured at a low cost, and may be installed throughout a building in the manner that automatic sprinkler systems are now employed but without the use of auxiliary piping, and which shall be capable of refilling, resetting and reuse.

In the accompanying drawings, in which is shown the preferred embodiments of my invention, and in which like reference numerals refer to similar parts throughout, Figure 1 represents a sectional elevation of an automatically operated fire extinguisher embodying my invention; Fig. 2 is a sectional view taken at right angles to the

plane of Fig. 1, showing the extinguisher in operation; Fig. 3 is a sectional elevation of a modification of my device as to the valve operating and sprinkling means; Fig. 4 is an enlarged view of the thermal control member and portions of the contiguous parts to which it is connected; Fig. 5 is a like view taken at right angles to the plane of Fig. 4.

Referring to the drawings in detail, the numeral 1 represents a cylindrical casing forming the sides of a container for the fire extinguishing fluid 2. This casing may be constructed of metal or any suitable vitreous material. The container is closed at the top by a cover 3 having a circular opening therethrough formed by the inturned flange 4 and by an upwardly projecting shell 5 fitted therein, externally screw-threaded to engage a hanger 6, which preferably seats upon a washer 7. Within the container is located the piston 8 having the upwardly projecting flange 9 forming a chamber between the cover of the container and the lower wall 10 of the piston, in which chamber is located the coiled spring 11. The piston wall 10 has the upwardly projecting boss 12 carrying the stem 13 adapted to project through the shell 5 and to receive through a hole 14 therein the pin 15 to hold the piston retracted against the force of the spring while the container is being filled with the fire extinguishing fluid and the automatic release mechanism is being set, as hereinafter described. The head of the piston has a packing ring 16 of suitable material preferably held thereagainst by a washer 17 and rivets 18. The boss 12 is internally screw-threaded to receive and engage the tubular nozzle 19 having the inlet port 20. The lower end of the tubular nozzle is closed and is pierced at its lower end with the spray outlets 21. The lower end of the container is closed by the bottom 22, both cover and bottom forming tight joints with the cylindrical casing 1. The bottom 22 has the filling orifice formed therein closed by the stopper 23, and a central port formed by the inturned flange 24 adapted to seat a circular beveled valve head 25. The valve head 25 is crowded upon its seat by the screw 26 carried by the bar 27 supported at one end by engagement with the pin 28 carried by the downwardly depending lugs 29 formed upon the bottom 22. The other end

of the bar 27 engages a fusible link member, shown in detail in Figs. 4 and 5. This fusible link comprises the hook 30 which is attached by solder 31 of low melting point to the plate 32 having the hole 33 therein adapted to register with the angular extension 34 of the downwardly extending hook 35 depending from the bottom 22. The particular feature of advantage realized by this release mechanism is that by application of the spring power nearer to the fulcrum of the lever than to the fusible link, it is possible to construct the link with a less amount of solder, so that it is readily fusible, and also that the link is ruptured before the solder is actually fused and as soon as it is appreciably softened, insuring positiveness as well as sensitiveness of operation upon the rise of temperature to the pre-calculated degree. When the valve head 25 is seated and the bar 27 placed in position, as shown in Fig. 1, the screw 26 is turned up to tightly set the valve head, which receives the thrust of the spring 11 transmitted to it by the tubular nozzle 19, upon the withdrawal of the setting pin 15. The distance from the point of support of the bar 27, between the screw 26 and the hook 30, is preferably greater than the distance from the point of support 28 to the screw 26, in order that the decreased leverage of the longer arm may place upon the hook 30 the lesser strain, so that the amount of solder necessary to hold the portions 30 and 32 in engagement will be a minimum, whereby the sensitiveness of the thermal conditions of the solder is increased, due to the small quantity necessary to hold the parts together, and the responsiveness of the device to rise in temperature is insured.

The method of operation of my device is as follows: The spring 11 being compressed by manual pressure upon the projecting end of the member 19, the stem 13 is projected through the cover and held in its retracted position by the pin 15. The filler cap 23 is removed and the container is filled, and the cap replaced. The valve head 25 is then seated and the bar 27 engaged at its extremity 28. The fusible link member is then hung upon the hook 34 and the bar member brought into association with its hook portion 30 and the screw 26 turned up to firmly seat the valve head in the orifice formed by the inturned flange 24, whose inner diameter is such as to permit the passage of the tubular member 19 therethrough in sliding contact therewith. Upon the melting of the solder 31 at the predetermined temperature at which it is calculated to flow, the force of the spring pulls the elements 30 and 32 apart, permitting the bar 27 to fall away, the force of the spring producing this effect before the solder has entirely melted and the tubular nozzle 19 is

gradually projected through the opening in the bottom of the container. The piston head 10 exerts the pressure of the spring upon the contained liquid 2, which flows through the orifice 20 into the tubular nozzle 70 and is expelled from the outlets 21 in the spray head. The piston then continues its travel until the contained liquid has been expelled, the spray nozzle continuing to be projected until the limit of travel is reached, 75 substantially as illustrated in Fig. 2. The shell 5 provides an air port therethrough for the admission of atmosphere in the rear of the piston by an opening through the eye-bolt 6 at its base.

In the modification of my device illustrated in Fig. 3 the tubular member 19 is replaced by the rod 36 attached to the piston head by the collars 37, whose lower end is terminated by the valve head 25 and the spray head 38. In this modification, upon the thermal release of the valve head the extinguishing fluid is expelled through the orifice in the bottom and is diffused in spray by the teeth 39 upon the spray head 38.

I have described my invention and the preferred form thereof as an automatically operated device, but it is obvious that said extinguisher is readily portable as a hand extinguisher and may be operated as such by manual release of the valve closure, hence I do not desire to be limited by said disclosure save as defined in the appended claims, since the particular features of advantage of the said invention are capable of structural embodiment in a variety of forms within the scope of its improvement over prior fire extinguisher devices.

I accordingly claim:

1. In an automatic fire-extinguisher, a container for a fire-extinguishing fluid, means adapted automatically to place said liquid under compression when a predetermined temperature is reached and means normally within said container adapted to 105 expel the fluid at a point exterior to said container.

2. In a fire-extinguisher, the combination of a container for a fire-extinguishing fluid, means adapted to place said liquid under 115 compression, and means adapted to be projected from said container for conveying said liquid to a point exterior to said container and there ejecting it.

3. In a fire-extinguisher, the combination 120 of a container for a fire-extinguishing fluid, means adapted to place said liquid under compression, and means for ejecting said liquid at a point exterior to said container, said means being positioned within said 125 container when the compression means is inactive.

4. In a fire-extinguisher, the combination of a container for a fire-extinguishing fluid, means adapted to compress said fluid and to 130

project a nozzle from said container, and means for causing said compression means to become operative.

5. In a fire extinguisher, the combination of a container for a fire extinguishing fluid, means adapted to compress said fluid mechanically, a member carried by said means and adapted to distribute said liquid under pressure, and a thermally controlled member adapted to support the force of compression transmitted by said member there-to until a predetermined temperature is reached and then to release both said compression means and said distributing mem- 15 ber.

6. In a fire-extinguisher, the combination of a container for a fire-extinguishing fluid, means adapted to place said liquid under compression, and means for ejecting said 20 liquid at a point exterior to said container, said means being positioned within said container when the compression means is inactive and adapted to be projected there- 25 from when the compression means become operative.

7. In a fire extinguisher, the combination of a container for a fire extinguishing fluid, a spring-driven piston therein, having an upwardly extending portion adapted to close 30 an opening in the top of said container and a downwardly extending portion adapted to project through an opening in the bottom of said container, a sealing member for said latter opening adapted to support the 35 said piston when retracted, and thermally-operable means for releasing said sealing member.

8. A thermally operative fire-extinguisher comprising a fluid container, a spring-driven 40 piston therein adapted when released to compress the contained fluid, a tubular member mounted upon the face of said piston, an opening for the admission of fluid thereto, and terminated at its lower ex- 45 tremity by a perforated head for the escape of said fluid, a circular orifice in the base of said container through which said tubular member may be projected upon the release of said spring, and means for holding said 50 spring in its retracted position, said means being adapted to release said spring and comprising a link fusible at a predetermined temperature.

9. In a thermally operative fire-extin- 55 guisher, means for automatically releasing its contents at a predetermined temperature comprising a valve normally seated and a spring actuated mechanism, said mechanism consisting of a compression member, a rigid 60 support therefor adapted to seat against said valve, and a temperature-responsive element tending normally to oppose said spring mechanism.

10. In a fire extinguisher, the combination 65 of a cylindrical container for a fire extin-

guishing fluid, means adapted to place said fluid under compression comprising a spring-driven piston therein, means for holding said piston in its retracted position comprising a member extending downwardly 70 from the face of said piston and adapted to be projected through an opening in said container upon the release of said spring, and a support for said member, said support constituting a sealing closure for said opening when the spring is retracted. 75

11. In a fire extinguisher, the combination of a cylindrical container for a fire extin- 80 guishing fluid, means adapted to place said fluid under compression comprising a spring-driven piston therein, an opening in said container, a valve-head adapted to close said opening, and a thermal release device adapted to keep said valve seated, with means for holding said piston in its retract- 85 ed position comprising a member extending through the face of said piston and normally seating upon said valve-head.

12. In a fire extinguisher, the combination of a container for a fire extinguishing fluid, 90 means adapted to place said fluid under compression comprising a spring-driven piston therein, a passage in the bottom of said container, an external closure for said passage adapted to seal same when the piston is 95 in retracted position, and means for holding said piston in its retracted position comprising a tubular member carried by said piston and adapted to seat upon said closure, the interiors of said tubular member 100 and of said container being in communication.

13. In a fire extinguisher, the combination of a cylindrical container for a fire extin- 105 guishing fluid, means adapted to place said fluid under compression comprising a spring-driven piston therein, an opening through said container, means for holding said piston in its retracted position comprising a closure for said opening, and a 110 tubular member axially aligned with said container and having an opening there- 115 through adjacent the face of said piston, the said member terminating in a nozzle adapted normally to rest upon said closure.

14. In a fire extinguisher of the class de- 120 scribed, the combination of a container for a fire extinguishing liquid comprising a cylindrical body portion, said top and bottom members each having a central opening therethrough, a piston in said container, and means for moving same comprising a spring coil in the head of said piston, an upwardly projecting portion of said head being adapted to register with the opening in the top of 125 the container when said spring is under compression, and a downwardly projecting portion of said head being adapted to register with the opening in the bottom of said container when said spring is released, and a 130

4
sealing member exterior to said casing adapted to close the opening in the bottom thereof when the piston is retracted and to be displaced by said piston upon the release 5 of said spring.

15. In a fire extinguisher of the class described, the combination of a container for a fire extinguishing liquid comprising a cylindrical body portion, and top and bottom 10 members each having a central opening therethrough, a piston in said container, and means for moving same comprising a spring coil in the head of said piston, an upwardly projecting portion of said head 15 being adapted to register with the opening in the top of the container when said spring

is under compression, and a downwardly projecting portion of said head being adapted to register with the opening in the bottom of said container when said spring is released, a sealing member exterior to said casing adapted to close the opening in the bottom thereof when the piston is retracted and to be displaced by said piston upon the release of said spring, a support for said 20 sealing member, and a fusible link associated therewith, said support holding said sealing member against the wall of said opening and receiving the thrust of the retracted piston and being adapted to be released by 25 the rupture of said fusible link.

J. STEWART THOMSON.
